UNITED STATES PATENT OFFICE.

WILLIAM CLARKE, OF AYR, SCOTLAND.

STEEL PILE.

No. 831,142.

Specification of Letters Patent.

Patented Sept. 18, 1906.

Application filed March 26, 1906. Serial No. 307,977.

To all whom it may concern:

Be it known that I, WILLIAM CLARKE, a subject of the King of Great Britain, residing at Ayr, Scotland, have invented certain new and useful Improvements in Steel Piles, of which the following is a specification, such as will enable those skilled in the art to which it appertains to make and use the same.

This invention relates to steel piles usually employed in the erection of coffer-dams for the purpose of subaqueous construction, such as for bridge-piers, also breakwaters, quay-walls, &c.; and the object thereof is to provide improved steel piling for both temporary and permanent work, which latter is to become incorporated with and forms a part of structures, such as retaining-walls, foundations, caissons, and for various uses of a similar nature. Where accuracy and expediency in the erection and solidity and strength in the work to which my invention has been applied become a material factor.

The invention is fully disclosed in the following specification, of which the accompanying drawings form a part, in which the separate parts of my improvement are designated by suitable reference characters in each of the views, and in which—

Figure 1 shows a cross-sectional view of one form of my improved steel piles, also two joints made with the adjoining members of a line of driven piles. Fig. 2 illustrates in plan view various forms of such piles and their adaptation to various manners of combining the same, and Fig. 3 shows in plan view a modified form of my invention especially adapted to form a flush face when joined together.

In the drawings forming part of this specification I have shown at *a* a section of a steel pile such as is suitable for a large range of engineering-work, especially for coffer-dam building in submerged locations where it is desirable to drive said piles for the purpose of inclosing certain areas, to have all joints in the driven line of piles easily accessible for calking purposes in order to prevent the inflow of water or quicksand into the inclosed area after having been pumped out. I accomplish this by means of my piles, which are of the well-known I-beam shape, the face of one flange being provided with a dovetail member *b*, while the face of the opposite flange is provided with a dovetail recess *c*. This dovetail recess *c* has an inwardly-extending additional recess *d*, which, like the dovetail *a*

and the recess *b*, extends the full length of the piles. These piles are rolled to the proper shape with flanges and webs of dimensions to correspond to the requirements of the special work for which they are designed. The additional recess *d*, oblong in cross-section, is utilized for the purpose of admitting calking material, as shown in Fig. 1, as soon as the piles are driven to place. For temporary work jute, oakum, waste, or clay is suitable, which when introduced and rammed into place will give the proper filling, will act as a wedge by driving the oblique sides of the dovetail into the corresponding sides of their recesses, and thereby making perfect and easy connection with water-tight joint.

In Fig. 2 I have shown a combination of straight, bent, and segmental piles—such as at *a* a right-angle corner-pile, at *f* a series of piles, at *g* an offset pile, and at *h* a series of segmental piles, all provided with dovetails *b* and recesses *c* and with apertures *d* to receive the above-mentioned calking material. The shaping of these piles in the various forms can easily be effected in the rolling-mills, and such shaping takes place entirely in the web of the same.

In Fig. 3 I have shown a straight pile *i*, made of the form of U-beams, with dovetails *b* and their recesses *c* and *d* on the outer faces of the opposite flanges. When driven together, these piles will form on one side straight flush faces, while the other side will present the projecting flanges locked together in the manner above described. This system of piling is especially useful whenever it is desired to incorporate driven piles into work which is designed for permanent use, such as piers. By backing up the inner face of such piling with concrete or other building stone material the projecting flanges form a good lock therewith, while the outer face will present a smooth and even surface. For the purpose of making these joints permanent and durable it is designed to place in the recesses *d* a mixture of sal-ammoniac and iron-dust. This calking material after having become set forms a hard air and water-tight joint and tends to make a system of steel piling of this kind, driven and joined together in this manner, a continuous mass impervious and solid. Such piles, if desired, can be made additionally strong and non-yielding by riveting or bolting a proper cap of U-beams or angle-iron to the top of the same.

Having fully described my invention, what

I claim as new, and desire to secure by Letters Patent, is—

1. In a steel pile, consisting of a rolled shape having a web member and two flanges, the latter provided with an interlocking device consisting of a dovetail which forms a part of one flange and is projected from the outer face thereof, and a dovetailed recess which forms part of the other flange and is extending into the face thereof, both dovetail and recess to be of corresponding shape and dimension to admit the insertion of the dovetail of one pile into the recess of another pile to be adjoined thereto so as to form a continuous series, and means for making said joint water-tight by the introduction of calking material into a place provided for this purpose and forming a part of the dovetailed recess above mentioned, substantially as shown and described.
2. A steel pile having flanges with interlocking devices of dovetail shape which latter form a member on the outward face of such flanges; and a web member rolled to either a straight, segmental or bent shape, in order to form by their use an interlocking, straight line, circular, or angularly-formed series of piles, each joint having an accessible recess for the purpose of introducing therein calking material, substantially as shown and described.

In testimony that I claim the foregoing as my invention I have signed my name, in presence of the subscribing witnesses, this 13th day of March, 1906.

WILLIAM CLARKE.
